UNITED STATES PATENT OFFICE

2,616,107

PAD SUPPORT

Napoleon S. Ferland, Beverly, Mass., assignor to
 United Shoe Machinery Corporation, Flemington, N. J., a corporation of New Jersey

Application April 5, 1951, Serial No. 219,431

9 Claims. (Cl. 12—38)

1

This invention relates to pad boxes, that is, to supports for a yielding pad as used in applying pressure to shoe bottoms, for example, in the cement-attachment of soles to shoes.

Usually a thick pad contoured to correspond to the transverse curvature of the shoe bottom is employed with a support adjustable to the longitudinal contour of the shoe bottom. Objects of this invention are to provide a pad support having transverse as well as longitudinal contours and which may be adjusted so that a thin yielding pad may be used therewith the function of which is to take care only of the minor differences between the contour of the pad and that of the shoe bottom, thus effecting economy in the use of relatively short-lived rubberlike materials used for the pad, and also to provide a pad support the transverse contour of which at the shank portion may be varied relatively to that of the forepart, the shank portion usually having the greater curvature.

To provide for adjustment of the longitudinal curvature of the pad support to correspond to the longitudinal curvature of the shoe bottom, transverse pivots in the support are located one at each end of the shank portion. Then, by fixedly supporting the heel end heightwise and variably supporting the heightwise positions of the ball joint and the forepart of the pad support, its longitudinal contour may be made complementary to the longitudinal curvature of any shoe bottom, that is, to the bottom of any shoe irrespective of the height of the heel which it is to have.

The variations of the transverse curvature of the pad supporting may be accomplished, as illustrated, by making the support of a plurality of independent longitudinally extending sections each having a pivot at each end of the shank-engaging portion and by providing a curved surface complementary to the transverse curvature of the forepart of the shoe bottom under the forepart of the pad support and another support under the ball joint of the sections complementary to the transverse curvature of the shoe bottom at the ball and shank. Since the sections are independent, they are shiftable relatively to each other longitudinally of the shoe to take care of any rearward curvature of the shoe bottom at the ball line. The longitudinally extending sections of the pad support may be made as numerous as desired, the greater the number the more closely they can be made to correspond to the transverse curve of the shoe bottom.

These and other features of the invention will 55 end portions of each shank portion 14 are cut

2

appear more fully from the following description when read in connection with the accompanying drawings and will be pointed out in the appended claims.

5 In the drawings—

Fig. 1 is a perspective view of the pad box and pad support;

Fig. 2 is a detail of a prismatic member which engages the pad support under the ball line;

10 Fig. 3 is a transverse sectional view showing the prismatic member supporting the forepart of the pad support;

Fig. 4 is a sectional view on the line IV—IV of Fig. 5;

15 Fig. 5 is a perspective view of one of the sections comprising the pad support;

Fig. 6 is a side elevation, partly in section, showing the pad support adjusted for a shoe that is to have a high heel; and

20 Fig. 7 is a view similar to Fig. 6 showing the support adjusted for a shoe having a relatively flat bottom.

The support for a pad 8 comprises a plurality, or even a multiplicity, of laterally narrow, longitudinally extending sections 10 (Fig. 5) of sufficient heightwise extent to provide the necessary strength to resist the applied pressure. Each of the longitudinally extending sections has three portions, a heel portion 12, a shank portion 14 and a forepart portion 16. Each of the sections (eighteen of which are shown in the drawings) has two flush joints, one, 18, substantially under the ball line of a shoe placed thereon and another, 20, under the heel breast line of the shoe.

35 In making the joints 18 and 20, the shank portion 14 is rounded at each end, one end being received by a complementary recess in the heel portion 12 and the other end being received in a complementary recess in the forepart portion 16. Plates, comprising a circular portion 22 and a stem portion 24, are placed one on each side of the joint between the adjacent portions of each section 10 with the circular portion 22 concentric with the curved end of the shank section and with the stem 24 overlying the adjacent heel or forepart portion. Each plate is recessed into the adjacent portions so as to be flush with their surfaces, the stem 24 being secured by rivets 26, and the joints being formed by a rivet 28 (Fig. 4) (which may be a hollow rivet) put through the center of the circular portions of the plates and through an end portion of the shank section to form the joint. The 40 45 50 55 end portions of each shank portion 14 are cut

sections each having two joints one at the ball line and one at the breast line, means supporting the heel portions of the sections heightwise, a support for the ball line joints of the sections, a support for the foreparts of the sections, and means for varying the heightwise position of the ball line support to vary the longitudinal curvature of the sections.

9. A pad support for use in applying pressure to shoe bottoms comprising a series of longitudinally extending, juxtaposed, pad-supporting sections each having a joint at the ball line and at the breast line thus dividing each section into a forepart portion, a shank portion and a heel portion, a fixed support sustaining the heel portions of the sections heightwise, a support for the ball joints of the sections comprising a prismatic

10

member rotatable about its longitudinal axis, the faces of said member being curved longitudinally thereof to different extents and each by rotation of said member being adapted to support the sections and to impart thereto a transverse curvature, and means for supporting the forepart portions.

NAPOLEON S. FERLAND.
